UNITED STATES PATENT OFFICE.

JOSEPH DANESE, OF PHILADELPHIA, PENNSYLVANIA.

EXTENSION DEVICE.

Application filed September 10, 1921. Serial No. 499,806.

To all whom it may concern

Be it known that I, JOSEPH DANESE, a citizen of the United States, residing at Philadelphia, in the county of Philadelphia and State of Pennsylvania, have invented 5 new and useful Improvements in Extension Devices, of which the following is a specification.

This invention relates to extension devices or retractile means whereby when an article is moved away from its normal position for use in another location it is automatically retracted thereafter. More specifically this invention has reference to extension means for connection to and use in conjunction with electric light, telephones and analogous articles of everyday usage.

The primary object of this invention is to provide a novel retractile means for connection into a length of electric light, telephone or other extension cable which will effectively recoil said cable when not in use or otherwise, as desired, whilst in no way impairing or injuring its covering or exterior surface.

Another object of this invention is to provide a retractile device which is simple in construction, cheap to manufacture, effective in use, not susceptible to derangement, whilst at the same time presenting an attractive appearance.

With the foregoing and other objects in view as will become more apparent as this description proceeds my invention consists 35 essentially in the novel details and features of construction, combinations and arrangements of parts hereinafter fully set forth and more specifically defined by the appended claims.

40 In the further disclosure of the invention reference is to be had to the accompanying sheets of explanatory drawings constituting a part of this specification, and in which like characters of reference designate the same or corresponding parts in all the views.

Figure 1— is a sectional view—on the line 1—1 in Figure 2— or through one form of my invention as adaptable for use in connection with an electric light extension cable with the socket and light connections shown by dotted lines.

50 Figure 2— is a central section taken at right angles to the preceding figure with the cable shown wound up therein in independent spiral coils.

Figure 3— is a reduced exterior face

view of the device shown in Figures 1 and 2.

Figure 4— is a fragmentary section on the line 4—4 in Figure 2— showing the position of antifriction rollers hereinafter further referred to.

Figure 5— is a section on the line 5—5 in Figure 2.

Figure 6— is a sectional view showing the means for connecting the cable to the inner rotatable part of the device.

Figure 7— is a sectional view of a modified form of the invention and in which the cable is wound up into an overlapping or single spiral coil.

Figure 8— is a section on the line 8—8 in the preceding figure.

Figure 9— is an enlarged sectional detail taken on the line 9—9 in Figure 8.

Figure 10— is a perspective view of the dash of an automobile showing the application of my invention thereto.

Figure 11— exemplifies the application of my invention to the extension cable of a telephone.

Figure 12— illustrates the application of the invention to a reading lamp.

Figure 13— illustrates an overhung electric street lamp having my invention associated therewith; and,

Figure 14— is an enlarged sectional detail of the lamp attachment shown in the preceding figure.

Referring to the drawings and more specifically to Figures 1 to 6 inclusive, I construct a circular casing or shell of thin sheet material and including front and back dished sections 15, 16, respectively, between which is interposed a wall or separating disc

90 17, said parts being rigidly connected together by an overlap joint 18 whereby two compartments 19, 20 are provided. Axially central of the front and back sections 15, 16, there is formed a recess that constitutes a 95 bearing 21 for an inner cylindric closed in

drum 22 which is adapted for free rotation between the bearings 21 on a square-shouldered axis or arbor pin 23 rigidly secured against rotation relative to the casing or shell by means of cap-screws 24 and lock washers 24' in the well known ways. Se-

urely fixed at one end as by a rivet 25 to the axis or pin 23 is one end of a spirally wound flat or recoil spring 26 the other 100 end whereof is similarly attached at 27 to the inner wall of the closed in drum 22.

105

110

Exteriorly of and centrally between the ends of the drum 22 is a circumferential friction-fit or integral rib or flange 23 adapted for free rotation in a channeled or 5 grooved bearing or raceway 29 formed about the inner apertured part of the hereinbefore referred to wall or separating disc 17 whereby it will be seen that the drum 22 and its connected or integrally formed rib 10 or flange 28 can be rotated about the axis or pin 23 in opposition to the recoil spring 26. Conveniently at two or more intervals about the peripheral edge of the rib or flange 28 I provide notches or inset teeth 30 15 for engagement by a spring influenced pawl or detent 31 pivoted in any convenient position within the aforesaid grooved bearing or raceway 29 to prevent accidental back motion of the drum 22 when not so desired and as later on explained.

Journalized in opposed outwardly directed channels or grooves 32 formed for the purpose in the front and back dished sections 15, 16, respectively, are radially disposed anti-friction rollers 33, the peripheral surfaces whereof project slightly beyond the inner faces of said sections; and in direct register with said rollers 33 are corresponding radial rollers 34 journaled in slots 35 in the 20 wall or separating disc 17 as will be clearly seen more particularly by reference to Figure 4 of the drawings. It is also to be noted from Figure 1 that the wall or separating disc 17 is also provided with opposed angular cut out portions 36 for the purpose later on explained whilst the rim of the device is formed with diametrically opposed lipped apertures 37 in axial alignment therewith.

In the practical application of my improved extension device to an electric light cable 38 for example as shown by the figures under specific explanation it is to be observed that said cable is secured at its medial part by passage through an aperture 39 provided for the purpose in the circumferential rib or flange 28 the registering part of the drum 22 being also indented at 40 so that the cable 38 is crushed to oval cross section as shown at 41 in Figure 3, whilst straps 42 or clips 42 are—or may be—attached thereto to obtain a secure attachment to the drum 22. The one-half of the cable 31 in the compartment 19—for example—is then coiled around the drum 22 in a clock-wise 45 direction or to the right-hand until said compartment is filled whereupon the free end is threaded through one of the angular cut out portions 36 and registering peripheral lipped aperture 37 to have connection with a screw plug 43—Figure 1—for attachment to a wall or ceiling socket 44 in the well known way. In like manner the other half of the cable 38 is wound in a clockwise or right handed direction about the drum 22 in the 50 compartment 20 with its free end passing out

of the opposed angular cut-out portion 36 and peripheral lipped aperture 37 for attachment to a lamp socket 45 in the well known way. Now it will be perfectly obvious that a pull exerted on the lamp socket 45 will result in an extension of the lamp cable 38 as desired with a consequential unwinding of both halves of said cable 38 in opposition to the recoil spring 26, whilst the spring influenced pawl or detent 31 will prevent any back motion by engaging in one of the teeth or notches 30, when the lamp has been extended to the requisite extent. To recoil the cable 38 a slight pull on the lamp socket 45 will disengage the pawl or 60 detent 31 and said cable will be automatically rewound into the casing under the action of the recoil spring 26 as will be clearly understood by those acquainted with the art to which my invention appertains. It is to 65 be here noted that during the extension or retraction of the cable 38 the antifriction and radial rollers 33, 34, serve to prevent any binding thereof as well as aiding in its rapid and free winding or unwinding. 70

In the modified form of the invention shown by Figures 7, 8 and 9 it will be seen that the casing of the extension device is not divided by any intermediate wall or disc 17 as hereinbefore set forth but that it consists of a single compartment 46 whilst the drum 22 is provided with spring influenced ball bearings 47 which considerably minimize friction in its rotation. Still further it is to be noted that the cable 38 is folded upon itself and connected by a single strap 48 at its medial or other point to the drum 22 whilst it is wound spiral fashion so doubled upon itself in a contra-clockwise or left-handed direction only between the anti-friction rollers 33. The use and operation of this form of the invention will be clearly apparent from the hereinbefore description with reference to Figures 1 to 6 inclusive, without further elucidation. 90

In the further description the extension device will be referred in its entirety by the reference character A.

Figure 10 shows the application of the extension device A to an electric light 49 attached to the dash 50 of an automobile 51 its purpose and functioning being clearly apparent.

Figure 11 illustrates the adaptation of the device A for attachment to a telephone 52 110 having an extension cable or wire 53.

Figure 12 exemplifies the utility of my extension device A in connection with a reading or table lamp 54 for attachment to a wall or floor socket 55.

In Figures 13 and 14 there is shown the application of the extension device A to an overhanging street lamp standard 56 supporting an arc-lamp 57 it being understood that a latch 58 is provided for locking said 130

lamp when in raised or normal position. Obviously the lamp 57 will be drawn down by means of a hooked rod or the like and will be returned under the action of its recoil spring 5 as hereinbefore fully set forth.

From the foregoing description and an examination of the drawings, it will be clearly seen that by my invention there is provided an exceedingly simple and effective extension 10 device for the several purposes referred to, and whilst I have outlined practical embodiments thereof the same are not to be construed as conclusive, in that various changes and modifications in the details of construction 15 and assembly of its parts will be obvious, and the right is hereby reserved to make such changes and variations as fairly fall within the scope of the appended claims.

Having described my invention, what I 20 claim as new and desire to secure by Letters Patent is:

1. An extension device for cables comprising a hollow casing, an axially concentric drum mounted on ball bearings and 25 rotatable within said casing, recoil means tending to restrain the rotation of said drum in one direction, and means for connecting a cable intermediate its ends to said drum about which it is coiled upon itself in a 30 single plane and with the free ends thereof projecting through peripherally opposed openings.

2. An extension device for cables comprising a hollow casing divided by a centrally apertured wall into parallel compartments, an axially concentric drum rotatably mounted within said casing, recoil means tending to restrain the rotation of said drum in one direction, a circumferential flange intermediate the ends of said drum rotatable in a grooved runway around the aperture in the aforesaid wall, notches in said flange and a spring influenced detent for arresting the rotation of the drum when desired, and 45 means for connecting a cable intermediate its ends to said drum, one portion of said cable being wound around the drum in one compartment to the right hand and the other portion being wound around the drum 50 in the other compartment in a like direction, the free ends of the cable projecting through diametrically opposed openings in the peripheral surface of said hollow casing.

3. An extension device for cables comprising a hollow casing divided by a centrally apertured wall into parallel compartments, an axially concentric drum rotatably mounted within said casing, recoil means 60 tending to restrain the rotation of said drum in one direction, a circumferential flange intermediate the ends of said drum rotatable in a grooved runway around the aperture in the aforesaid wall, notches in said flange and a spring influenced detent for arresting 65

the rotation of the drum when desired, radially disposed antifriction rollers in the walls of said casing, and means for connecting a cable intermediate its ends to said drum, one portion of said cable being wound 70 around the drum in one compartment to the right hand and the other portion being wound around the drum in the other compartment in a like direction, the free ends of the cable projecting through diametrically opposed openings in the peripheral surface of said hollow casing.

4. An extension device for cables comprising a hollow casing divided by a centrally apertured wall into parallel compartments, an axially concentric drum rotatably mounted within said casing, recoil means tending to restrain the rotation of said drum in one direction, a circumferential flange intermediate the ends of said drum 80 rotatable in a grooved runway around the aperture in the aforesaid wall, notches in said flange and a spring influenced detent for arresting the rotation of the drum when desired, radially disposed antifriction rollers 85 in the walls of said casing, a cable passed through an aperture in the aforesaid circumferential flange and an indent in the rotatable drum whereby it is compressed to prevent longitudinal displacement, one portion of said cable being wound 90 around the drum in one compartment to the right hand and the other portion being wound around the drum in the other compartment in a like direction, the free ends of the cable projecting through diametrically opposed openings in the peripheral surface of said hollow casing.

5. An extension device for cables comprising a hollow casing divided by a centrally apertured wall into parallel compartments, an axially concentric drum rotatably mounted within said casing, recoil means tending to restrain the rotation of said drum in one direction, a circumferential flange intermediate the ends of said drum rotatable in a grooved runway around the aperture in the aforesaid wall, notches in said flange and a spring influenced detent for arresting the rotation of the drum when desired, radially disposed antifriction rollers in the walls of said casing, a cable passed through an aperture in the aforesaid circumferential flange 105 and an indent in the rotatable drum whereby it is compressed at that point, straps adjacent said flange for securing the cable against longitudinal displacement, one portion of said cable being wound around the drum in one compartment to the right hand and the other portion being wound around the drum in the other compartment in a like direction, the free ends of the cable projecting through diametrically opposed openings in the peripheral surface of said hollow casing.

6. The combination with an electric light or telephone extension cable of a hollow casing divided by a centrally apertured wall into parallel compartments, an axially concentric drum rotatably mounted within said casing, recoil means tending to restrain the rotation of said drum in one direction, a circumferential flange intermediate the ends of said drum rotatable in a grooved runway around the aperture in the aforesaid wall, notches in said flange and a spring influ-

enced detent for arresting the rotation of the drum when desired, an aperture in the aforesaid circumferential flange and an indent in the rotatable drum through which 15 the cable is passed and secured intermediate its ends, said cable being wound around the drum in like directions in the parallel compartments.

In testimony whereof I affix my signature. 20

JOSEPH DANESE.
